UNITED STATES PATENT OFFICE

ROBERT A. CHRISTIE, OF GLENSIDE, PENNSYLVANIA, ASSIGNOR TO PAPERCRAFT CORPORATION, OF ELKINS PARK, PENNSYLVANIA, A CORPORATION OF PENNSYLVANIA

CLEANING AND POLISHING PAPER

Application filed March 28, 1930. Serial No. 439,713.

Objects of the present invention are to provide for cleaning and polishing various articles, for example, eye-glasses; to provide a medium for that purpose which shall be comparatively inexpensive and yet efficient; and to provide such a medium in form and at a cost that will permit of its being bound up in the form of little booklets carrying advertisements and adapted to be given away.

10 Other objects of the present invention will appear from the following description at the end of which the invention will be claimed.

Generally stated, the invention consists of a sheet of crepe paper, tissue, kraft or sulfite, having a facially arranged cleaning compound, rouge, Bon Ami or the like, deposited and held in the folds of the crimps thereof and releasable by stretching the paper in use. One face of the paper may be plain 20 or uncoated and used for polishing and the other face of the paper may be impregnated or coated as described and used for cleaning along with moisture, if desired, such as can be provided by breathing on the article to be 25 cleaned.

The invention also comprises the improvements to be presently described and finally claimed.

In the following description reference 30 will be made to the accompanying drawings in which

Figure 1 is a diagrammatic view of a sheet of crepe paper embodying features of the invention.

35 Fig. 2 is a similar view illustrating to an enlarged scale a transverse section of the paper, and

Fig. 3 is a view similar to Fig. 2 illustrating a modification in which both sides of the paper are impregnated or coated in the manner described.

In the drawing 1 is a sheet of crepe paper having a deposit 2 of cleaning compound held in the folds 3 of the crimps and releasable by 40 the stretching of the paper which occurs in

use. As shown in Figs. 1 and 2 the other face of the paper is not coated and is available for polishing any surface that has been cleaned by the coated face. As shown in Fig. 3, both faces of the paper are coated in the manner 50 described.

The coating may be deposited on the paper before or after it is crimped. The described paper may of course be used dry. The paper may be put up in the form of small booklets or in the form of rolls or sheets.

I claim:

1. As an article of manufacture a sheet of crepe paper having dry cleaning compound deposited and held in the folds of the crimps 60 thereof and on the face of the paper.

2. As an article of manufacture a sheet of crepe paper having on one face a deposit of dry cleaning compound held in the folds and crimps and having the other face devoid of 65 the cleaning compound and available for polishing.

ROBERT A. CHRISTIE.
